CLAIM

The ornamental design for a sandal, as shown and described.

DESCRIPTION

FIG. 1 is a top plan view of a sandal showing my new design;

FIG. 2 is a bottom plan view thereof;

FIG. 3 is a right side elevational view thereof;

FIG. 4 is a left side elevational view thereof;

FIG. 5 is a front elevational view thereof;

FIG. 6 is a rear elevational view thereof; and,

FIG. 7 is a top plan partial cutaway view thereof.

The stippling in FIGS. 1 and 7 represents a translucent material.
